US00D573352S

(12) **United States Design Patent**
Sollars, Jr.

(10) **Patent No.:** **US D573,352 S**
(45) **Date of Patent:** ** *Jul. 22, 2008

(54) **INFLATABLE AIRBAG WITH CLOSELY SPACED JOINTS**

(75) Inventor: **John A. Sollars, Jr.**, LaGrange, GA (US)

(73) Assignee: **Milliken & Company**, Spartanburg, SC (US)

(**) Term: **14 Years**

(21) Appl. No.: **29/192,727**

(22) Filed: **Oct. 30, 2003**

Primary Examiner—T. Chase Nelson

(74) *Attorney, Agent, or Firm*—Terry T. Moyer; John E. Vick, Jr.

(57) **CLAIM**

The ornamental design for an inflatable airbag with closely spaced joints, as shown and described.

DESCRIPTION

FIG. 1 is a perspective view of a first embodiment of the invention;

FIG. 2 is a perspective view of a second embodiment of the invention;

FIG. 3 is a perspective view of a third embodiment of the invention;

FIG. 4 is a perspective view of a fourth embodiment of the invention; and,

FIG. 5 is a perspective view of a fifth embodiment of the invention.

1 Claim, 3 Drawing Sheets
